UNITED STATES PATENT OFFICE.

DE ROY AUSTIN, OF OMAHA, NEBRASKA.

INSOLE FOR SHOES.

981,154.

Specification of Letters Patent. Patented Jan. 10, 1911.

Application filed September 7, 1909. Serial No. 516,617.

To all whom it may concern:

Be it known that I, DE ROY AUSTIN, a citizen of the United States, and a resident of Omaha, in the county of Douglas and 5 State of Nebraska, have invented certain new and useful Improvements in Insoles for Shoes, of which the following is a specification.

My invention relates to insoles for boots 10 and shoes, and it is the object thereof to provide in a boot or shoe an insole of relatively heavy material having transverse reduced portions by which the same is rendered flexible, and having said trans- 15 verse reduced portions reinforced by resilient material so that the insole will not be weakened and also to provide a resilient or cushioned tread.

In shoes for many purposes it is desirable 20 that the soles thereof be made flexible so as to bend easily and permit a natural movement of the foot in walking. Such flexibility is ordinarily attained by the use of thin soles and insoles, but the use of thin 25 material, especially for insoles, is objectionable for the reason that at the edges of the sole where it is attached to the upper and welt there is insufficient material to give the necessary strength. As a result the insole 30 soon gives way at the edges and the shoe is thus lacking in durability. It is also desirable in shoes having cushioned insoles that the cushioning material be so held in position as to overcome any tendency there- 35 of to bunch or lump, thereby becoming thinner at the points which receive the greatest pressure and thicker at those parts which receive lighter pressures.

My invention provides a means for attaining the above desired results.

In the accompanying drawings, Figure 1 is a partial longitudinal vertical section through a shoe having an insole constructed in accordance with my invention, Fig. 2 is 45 a transverse vertical section of the same on the plane of the line $x-x$ of Fig. 1, and Fig. 3 is a bottom plan of the insole and welt with the outsole removed therefrom.

In that embodiment of my invention illus- 50 trated in the drawings, the upper 1, the welt 2 and the outsole 3 are all of ordinary construction and arrangement. The insole 4 is of relatively heavy material such as is ordinarily used for shoes constructed for durability and without regard for flexibility of 55 the sole, so that at the edges of the sole

where, the same are secured to the welt and upper there is ample material to make a strong and durable seam. In the front part of the insole, or from the instep to the toe, 60 a number of transverse channels or grooves are made in the lower side thereof, the said channels being of uniform depth and the width thereof being somewhat greater than that of the transverse tongues or ribs of 65 material 5 which are left between the channels. In said transverse channels are placed strips 6 of resilient material, such as felt. The said strips of material are rectangular in section and the normal thickness thereof is 70 made greater than the depth of the trans- 75 verse channels so that when the material is compressed it will as nearly as possible just fill the channels and the lower surface thereof lie flush with the lower surface of the transverse tongues 5 between the channels. The ends of the strips 6 are shaped to conform to the outline of the sole, as shown in Fig. 3, the said strips and the channels terminating inside the feather 7 through which the insole is sewed to the upper and welt. Between the insole and outsole a thin sheet 8 of felt or other suitable material may be placed, and when such sheet is used the same is preferably cemented in place. 85

It will be obvious that by the construction shown a shoe may be provided with a heavy and durable insole which may be readily flexed or bent to accommodate the natural bending movement of the foot in walking. 90 The sole at the thinned or weakened portions thereof made by the transverse channels is sustained by the strips of resilient material so that it will not break down along the lines of the channels. It will also be apparent that the insole, in addition to its flexibility, will be so supported by the resilient material thereunder as to yield locally under the points of greatest pressure so as to conform to the shape of the foot and provide a cushioned or resilient tread, and that the strips of resilient material are so held in position by the transverse ribs or tongues 5 that the same cannot be displaced or the cushioning material become unevenly distributed as is liable in cushioned soles where the cushioning material is not so held to its proper position. 95 100 105

Now, having described my invention, what I claim and desire to secure by Letters Patent is:

1. In a shoe, an outsole, an insole formed

from a relatively thick sheet of material having transverse thinned portions alternating with tongues of the full thickness of the sheet, strips of a different material arranged to support the thinned portions of the sheet and normally extending below the tongues thereon, and means for connecting to each other the edges of the outsole and insole.

2. In a shoe, an outsole, an insole, means 10 for connecting to each other the edges of said outsole and insole, the insole comprising a relatively thick sheet of material having transverse channels formed in the side thereof of adjoining the outsole and integral trans- 15 verse ribs between said channels, and strips of a different material arranged in said channels, the said strips normally projecting beyond the ribs to hold the outsole and insole in spaced relation to each other.

20 3. In a shoe, an outsole, an insole, means for connecting to each other the edges of said outsole and insole, the insole comprising a relatively thick sheet of material having transverse channels of uniform depth 25 formed in the under side thereof and integral transverse ribs between the channels, and strips of resilient material disposed in said channels, said strips being of a thickness greater than the depth of the channels 30 so as to normally project below the ribs and hold the outsole and insole in spaced relation to each other.

4. In a shoe, an outsole, an insole having 35 transverse channels formed in the under side thereof from the instep to the toe, said channels terminating inside the welt-feather, strips of resilient material disposed in said channels, and a relatively thin sheet of resilient material secured between the insole and the outsole.

40 5. In a shoe, an outsole, an insole, a welt connecting to each other the edges of said outsole and insole, the insole having trans- 45 verse channels made therein and terminat- ing inside the welt, and strips of resilient material disposed in said channels and normally holding the outsole and insole in spaced relation to each other.

6. In a shoe, an outsole, an insole, a welt 50 connecting the outsole and insole at the edges thereof, the insole having transverse

channels formed in the under side thereof and terminating inside the welt, and cushioning material disposed between the outsole and insole, to hold the same yieldably 55 in normally spaced relation to each other, the said cushioning material consisting of strips fitting into the transverse channels in the insole, the strips being of greater depth than the channels. 60

7. In a shoe, an outsole, an insole, a welt connecting the same at the edges thereof, the insole being formed from a sheet of material having transverse thinned portions alternating with tongues of the full thickness 65 of the sheet, the thinned portions terminating inside the welt, and cushioning material disposed between the outsole and insole to hold the same normally in spaced relation to each other, the said cushioning material fitting into the space between the unthinned portions of the sheet to support the thinned portions thereof.

8. In a shoe, an upper, an insole, a welt, means connecting the same, an outsole se- 75 cured to the welt, the insole having trans- verse channels made in the under side there- of adjoining the outsole, the said channels terminating inside the portion of the insole connected with the welt, and strips of re- 80 sili-ent material disposed in said channels; said strips being normally of greater depth than the channels, whereby the same hold the insole normally in a spaced relation to the outsole. 85

9. In a shoe, an outsole, an insole having at its central part thinned portions and unthinned portions, means for connecting to each other the edges of the outsole and insole, and pieces of resilient cushioning ma- 90 terial inserted in the lower side of the insole to support the thinned portions thereof and to normally hold the outsole and the unthinned portions of the insole in spaced relation to each other. 95

In testimony whereof I have hereunto subscribed my name in the presence of two witnesses.

DE ROY AUSTIN.
